TRAFFIC LIGHT

Max Dapoz, New Philadelphia, Ohio, assignor of
one-fifth to Henry Thiebaud, and one-fifth to
Joseph F. Sani, both of New Philadelphia, Ohio

Application March 7, 1951, Serial No. 214,299

3 Claims. (Cl. 340—43)

1

This invention comprises novel and useful improvements in traffic control lights, and more particularly pertains to a traffic control light of the type having an indicator moveably mounted thereon to indicate the time remaining during which a certain light will be actuated.

An important object of this invention is to provide a traffic control light having a pair of relatively transverse light units, each of which units have an indicator moveably mounted thereon to indicate the time remaining during which "Go" light, in each unit, will be actuated, which indicator is moved only when the "Go" light with which it is associated is energized, to thereby preclude drivers who are waiting out a "Stop" signal, from knowing prior to the time the "Stop" signal changes to "Go," just when the signal will change, which device nevertheless informs the motorists, who can see the "Go" signal of the other traffic light unit, of the time remaining during which the "Go" signal will be illuminated.

Another important object of this invention is to provide a traffic control light, in accordance with the foregoing object, in which the indicators may be driven by a common motor in a complete path about the "Go" light, with which they are associated, at relatively different rates of speeds, so that the duration of actuation of the "Go" lights of the relatively transverse light units, may be relatively different.

Yet another object of this invention is to provide a traffic control light, in accordance with the foregoing objects in which the motor which drives the indicators, times the actuation of the lights in both of the units, and also times the actuation of the mechanism for selectively drivingly connecting each of the indicators to the motor, whereby variations in the speed of the motor will not adversely effect the relative timing of the lights and indicators.

An important feature of this invention resides in the provision of a pair of relatively transverse light units, each having an indicator mounted for movement around one of the lights thereof to indicate the time remaining during which that light will be actuated, with a common motor for driving both of the indicators, and means for simultaneously, alternately drivingly engaging one of the indicators with the motor while disengaging the other of the indicators from the motor, to thereby permit the indicators to be driven at relatively different rates through a given path of movement, by a single motor.

Yet another feature of this invention resides in the provision of the traffic control light, in

2

accordance with the foregoing feature, with a mechanism controlled by the motor for actuating the means for engaging and disengaging the indicators from the motor, whereby variations in the speed of the motor will not affect the relative timing of the movement of the indicator and the time at which the indicator will be operatively disconnected from the motor.

Still another feature of this invention resides in the provision of a traffic control light, in accordance with the foregoing features, in which the motor also controls the energization of the other lights in each unit, whereby variations in the speed of the motor will not affect the timing of the energization of the lights and the movement of the indicators.

A further feature of this invention resides in the provision of a traffic control light, including a housing with relatively perpendicular lights thereon, and indicators each mounted in the housing for rotation about a horizontally disposed indicator support shaft, together with a motor having a vertically disposed drive shaft, and clutch means carried by the support shafts for selectively drivingly engaging the support shafts and the drive shafts, with a clutch actuator engaging each of the clutch means to move one into its engaging position while moving the other into its inoperative position.

These, together with various ancillary objects and features are attained by this device, the preferred embodiment of which has been illustrated in the accompanying drawings wherein;

Figure 1 is a side elevational view of the traffic control lights;

Figure 2 is a horizontal sectional view, taken on the plane 2—2 of Figure 1;

Figure 3 is a fragmentary vertical sectional view, taken on the plane 3—3 of Figure 2;

Figure 4 is a fragmentary vertical sectional view, taken on the plane 4—4 of Figure 3;

Figure 5 is a fragmentary vertical sectional view, taken on the plane 5—5 of Figure 2, showing the indicator lamp housing;

Figure 6 is a fragmentary side elevational view of the clutch actuator plate, and the means for rotatably supporting the same on the standards;

Figure 7 is a diagrammatic view of the wiring circuits for the lights, and the clutch actuator;

Figure 8 is perspective elevational view of the clutch actuator plate; and

Figure 9 is a fragmentary horizontal sectional view, taken on the plane 9—9 of Figure 3.

Reference is now made more specifically to the accompanying drawings wherein there is illus-

trated a traffic signal light, indicated generally by the numeral 10 which includes a housing 12, indicator light assemblies 14, a clutch mechanism 16 for operatively connecting the indicator lights to a motor drive shaft, and a timer assembly 18.

The housing 12 includes a bottom wall 20 which may be mounted upon a supporting post 22, as by the mounting flange 24, and upstanding side walls 26, 28, 30 and 32 are secured to the bottom wall as by the angle irons 34 and fasteners 36, best shown in Figure 4. A cap member 38 is secured to the upper ends of the side walls, as by fasteners 40.

Each of the side walls 26 and 28 are provided with vertically spaced apertures or openings, an upper lamp housing 42 which is disposed in one of the openings and secured thereto as by the flange 46, and a spirally-formed transparent tube 44 is disposed in the housing 42 and filled with a suitable inert gas which will emit a red glow, when suitably energized by electricity. An intermediate lamp housing 48 is disposed in another of said openings and secured thereto by the flange 52 and a helical transparent tube 50 is disposed in the housing 48, which tube is filled with an inert gas which will emit a yellow or amber glow when energized by a source of electrical potential. The lower opening 54, in the side walls 26 and 30 is provided for the reception of the transparent tube, shaped as is best shown in Figure 1 to provide inner and outer concentric coils 56 and 58, which coils are filled with an inert gas which will emit a green glow, when energized. The relatively parallel side walls 28 and 32, which side walls are disposed transversely of the side walls 26 and 30 are also provided with a plurality of vertically spaced openings an upper lamp housing 60 being mounted in one of the openings, as by the flange 62 with a suitable red lamp 64 disposed in the housing, and an intermediate housing 66, as mounted in the side walls 28 and 32 below the upper housing, by the flange 68, and an amber lamp 70 is disposed in the intermediate housing. The lower opening 69 in the side walls 28 and 32 has a green lamp 72 formed in the same manner as the corresponding lamp on the side walls 26 and 30. It may be noted, at this time, that the lamps and lamp housing on the side walls 26 and 30 are spaced vertically above the corresponding lamps and lamp housing on the side walls 28 and 32, for reasons which will later become apparent as the following description proceeds. Additionally, it will be appreciated that it is not imperative that there be provided four similar lamp units, one on each of the side walls, it merely being necessary, for the purposes of this invention, to provide a pair of lamp units, each disposed on relatively transverse side walls such as 28 and 30.

A rectangular inner casing 74 including side panels 76 is disposed within the housing 12, with one of the side panels paralleling each of the side walls of the housing which casing is secured to the bottom 20 of the housing, as by corner posts 78, and the top panel 80 which is secured to the corner posts, by fasteners 82, and which overlies the upper ends of the side panels of the casing. Bushings 84 are carried by each of the side panels 76, in registry with each of the openings 54 and 69 in the side walls of the housing, and an indicator support shaft 86 is rotatably journaled in each of the bushings.

An indicator light assembly 14 is mounted on the end of each of the shafts 86 and includes a

dish-shaped housing 88 which is secured to the shaft as by the nut 90, and which housing has an inwardly directed flange 92 adjacent to the open end thereof by means of which the opaque front panel 94 is secured to the housing. An indicator lamp 96 is mounted in the socket 98 carried by the indicator light housing 88, in registry with an opening 100 in the front panel 94, which opening is laterally offset from the axis of rotation of the housing 88. It is contemplated that the housing 88 be either formed of an electrically insulative material, so that the slip rings 102 and 104 which are secured, by fasteners 106 and 108 respectively to the back of the housing, will be electrically insulated from each other, and from the remainder of the traffic signal light. Alternatively, if the housing 88 is not formed of insulative material, the slip rings may be insulated therefrom, in any conventional manner. As is best shown in Figure 2, the slip rings 102 and 104 are each electrically connected to the lamp socket 98, by conductors 110, and suitable brushes 112 and 114, are secured to one of the side panels 76 of the casing 14, each of the brushes respectively contacting the slip rings 102 and 104.

It will thus be appreciated that as the housing 88 rotates about the shaft 86 that the lamp 96 may be illuminated through the intermediary of the brush and slip ring assembly, described above. As each of the indicator light assemblies 14 are the same, a description of one of the assemblies is deemed sufficient.

A motor (not shown) is disposed within the lower portion of the casing 74 and has a drive shaft 116 which extends through the bushing 118 in the partition 120, a first and a second set of bevelled drive gears 120 and 122 being non-rotatably secured to the shaft 116, in longitudinally spaced relation to each other. A first set of bevelled gears 124 are disposed in meshing engagement with the drive gear 120, which driven gears are rotatably supported for movement about a horizontal axis, on the journals 126 carried by the partition 120. A clutch member 128 is secured in the stub shaft (not shown) which supports the bevelled gears 124, and is movable with the latter, and a relatively movable mating clutch member 130 is disposed in sliding, but relatively non-rotatable engagement with the indicator assembly support shafts 86. Thus, when the clutch member 130 is moved axially of the shaft 86, into and out of engagement with the clutch member 128, the indicator support shaft 86, and the housing 88 carried thereby is drivingly connected to the drive shaft 116.

A plurality of vertically disposed standards 132 are secured to the partition 120, in any desired manner, and extend upwardly therefrom, a horizontally disposed rod 134 being secured between adjacent standards as is best shown in Figures 2 and 4. A clutch actuating yoke 136 has one end thereof vertically pivotally attached, as at 138 to the rod 134, and retained in position by collars 140. The yoke 136 has a pair of inwardly directed fingers 142 which engage in the recess 144 in the mating clutch member 130, whereby the clutch actuating yoke is operatively connected to the movable clutch member 130. The other of the drive gears 122 is in meshing engagement with a driven bevelled gear 146 carried by a stub shaft (not shown), which stub shaft is rotatably supported on the journal 148 (see Figure 3). Mating clutch members 150 and 152 are respectively carried by the stub shaft

upon which the driven gear 146 is secured, and the indicator light support shaft 86, which clutch members are movable into and out of driving engagement by means of the yoke 154 which is vertically pivotally mounted on the rod 155, which latter rod is disposed transversely of the rods 134 and spaced vertically therefrom, as is best shown in Figures 3 and 4. It is contemplated that the yoke 154 be operatively connected to the movable clutch member 152, by pins 158 which extend into the peripheral recess 160, whereby vertical pivotal movement of the yoke will cause movement of the clutch member 152 into and out of driving engagement with the mating clutch member 150.

It is to be noted, at this time, that the driven gears 146 which drive the indicator light assemblies carried by the side walls 26 and 28 of the housing are spaced vertically above the corresponding drive gears 124 which serve to drive the indicator light assemblies carried by the side walls 28 and 32 of the housing. Thus, either the gears 122 and 146 or the gears 120 and 124 may be interchanged with gears of a different size to vary the number of revolutions of the drive shaft 160 necessary to cause a complete revolution of the indicator support shaft 86 which is operatively connected to the driven gears 124 and 146.

In order to actuate each of the clutch members simultaneously, there is provided a clutch actuator plate 162, best shown in Figure 8. The plate 162 is substantially circular, and is rotatably supported by its periphery on the grooved rollers 164 which are journaled on stub shafts 166, intermediate the ends of the standards 132, as is best shown in Figure 6. The central portion of the actuator plate 162 is cut away, as at 168, to provide clearance for the drive shaft 116 and the associated clutch mechanisms, which actuator plate has a diametrically extending laterally offset portion 170. A first set of slots 172 are formed in the portion of the actuator plate 162, which slots receive the shank portion of the yokes 154, and a second set of slots 176 are formed in the laterally offset portion 170, and receive the shank portion of the yoke 136, as is best shown in Figures 2 and 4. It is to be noted that the slots 172 and 176 are not disposed concentric with the axis of rotation on the actuator plate 162, but are instead so constructed and arranged that counterclockwise movement of the actuator plate, as viewed in Figure 2, will cause the yokes 154 to be cam actuated out of their clutch engaging position, and the yokes 136 cam actuated into their clutch engaging position. Thus, movement of the actuated plate 162 in one direction causes a first pair of opposed indicator light assemblies 14 to be drivingly connected to the drive shaft 116, while the opposite movement of the actuator plate 162 drivingly engages the relatively transverse pair of indicator light assemblies with the drive shaft, and disengages the other pair therefrom.

In order to selectively pivot or swing the actuator plate 162 there is provided an upwardly extending bracket 178 which is secured to the partition 120, and which has a bellcrank 180 vertically pivotally attached to the upper end thereof, as by a pivot pin 182. A link 184 is pivotally attached by a fastener 186 to one leg of the bellcrank 180, and otherwise pivoted to an ear 188, by a pin 190, which ear is secured to the actuator plate 162, adjacent the periphery thereof (see Figure 3). A solenoid 192 is supported by

bracket 194 on the top panel 80 of the casing 74, the plunger 196 of the solenoid being connected by a link 198 to the leg of the bellcrank 180 other than that to which the link 84 is attached. It is contemplated that the plunger of the solenoid 192 will be retracted, when the latter is energized, whereby the link 198 will pivot the bellcrank 180 in a direction to cause clockwise movement of the actuator plate, as viewed in Figure 2. A tension spring 200 is secured to the same leg of the bellcrank 180 as the link 198 is attached, which spring is otherwise secured to a lug 202 carried by the partition 120, whereby the spring will yieldingly bias the bellcrank in a direction to cause counterclockwise movement of the actuator plate 162, as the latter is viewed in Figure 2. A combined guide and stop member 204 is formed integrally with the upper end of the bracket 178, and embraces opposite sides of the bellcrank 180 to guide the same in vertical pivotal movement, the web portion of the bifurcated guide 204 serving as a stop to limit downward pivotal movement of the bellcrank.

It is also contemplated that the motor which drives the indicator light assemblies 14 also serve to control the cyclic actuation of the lights, and the shifting of the clutch actuator plate 162, by the solenoid 192, and for this purpose, there is provided a U-shaped stand 206 which is secured to the partition 120, and has the web portion 208 thereof disposed in vertical spaced relation to the partition, in overlying relation to the clutch assemblies. A U-shaped plate 210 has the legs thereof secured to the web 208 of the U-shaped bracket 206, and an L-shaped bracket 212 has one leg thereof secured to the plate 210, with the other leg of the L-shaped bracket extending parallel to the plate 210, in vertical spaced relation thereto. A contact arm pivot pin 214 is secured, as by fasteners 216 and 218 to the bracket 212 and plate 210 respectively, and contact arms 220, 222, 224 and 226 are each secured to blocks 228, as by fasteners 229, whereby the contact arms are horizontally pivotally mounted on the pin 214.

An L-shaped contact post support member, 230, of electrically insulative material, is secured by fastener 232 to one of the side panels 76 of the casing 74 and extends through an opening 234 in that side panel. A first set of contact terminals 236 and 238 are secured to the member 230, and disposed in the path of movement of the contact arm 220; a contact terminal 240 also being secured to the member 230 and disposed in the path of movement of the contact arm 222; a pair of contacts 242 and 244, also carried by the insulative member 230, are disposed in the path of movement of the arm 224, while a contact terminal 246, on the member 230, is disposed in the path of movement of the arm 226.

The upper end of the drive shaft 116 is journaled in the web portion 208 of the U-shaped bracket 206, and has a spur gear 248 non-rotatably attached thereto, and the meshing engagement with a gear 250 on the cam shaft 252. This latter shaft is rotatably journaled at its upper end in the bracket 212 and at its lower end in the plate 210, and web 208 of the bracket 206. Cams 254, 256, 258 and 260 are non-rotatably attached to the cam shaft, and suitably spaced thereon by spacers 262. Springs 264 are attached to one end of each of the contact arms and to the bracket 212, to yieldingly urge the contact arms 220, 222, 224 and 226 respectively into engagement with the contact terminals 238, 240,

244 and **246**. The block **228** on each of the arms rides against its respective cam whereby the contact arms are each cyclically pivoted about the pin **214**, in opposition to the spring **264**, into contact with the opposed contact terminals, as will be best appreciated from a consideration of Figure 7.

The arm **220** is connected by conductor **266** to a source of power, the contact terminal **236** being connected by conductors **268** to the red lamps **44**, while the contact terminal **238** is connected by conductors **270** to the red lamp **64**. The contact arm **222** is also connected by a conductor **272** to a source of power, while the contact terminal **240** engaged thereby is connected by conductors **274** to the caution or amber lamps **50** and **70**, the cam **256** being suitably designed to close the contact between the arm and the terminal **240**, twice each revolution of the shaft **252**. The arm **224** is also connected by a conductor **276** to a source of power while the contact terminal **242** is connected by conductors **278** to the green lamps **72**, the contact terminal **244** being connected by conductors **280** to the green lamps **58**. The solenoid actuating control arm **226** is also connected to the source of power, as by conductor **282**, and the contact terminal **246** engaged thereby is connected by the conductor **284** to the solenoid **192**, so as to energize the latter upon closing of contact between the arm **226** and terminal **246**.

In operation, assuming that the motor drives the driven shaft **116**, through suitable reduction gearing, one revolution per minute, and the gear **124** is driven by the shaft **116**, and completes a revolution in thirty seconds, the gear **146**, also driven by the shaft **116**, completing one revolution in twenty seconds. The gears **248** and **250** are then so constructed that the cam shaft **252** will complete one revolution in fifty seconds, or the composite time necessary for both the gears **124** and **146** to complete one revolution.

Cam **260** is so dimensioned that the lobe thereof will retain the arm **226** out of engagement with the terminal **246** for three-fifths of the revolution of the cam shaft. While the arm **226** is out of engagement with the terminal **246**, the cam **258** moves the arm **224** into contact with the terminal **242**, to energize the green lamps **72**, and the indicating lights **96** carried thereby, whereby those indicating lamps which are being rotated by the drive shaft **116** will be simultaneously energized.

Obviously, when the green light **72** is actuated, the cam **254** moves the arm **220** into contact with the terminal **236**, to energize the red lamps **44** on the relatively transverse set of lamps, it being understood that the cam **256** will actuate the caution lights **50** and **70**, a predetermined time interval, such as three seconds, prior to the deactivation of the respective green lamps, and indicating lamps **96**.

As a single motor is utilized to control rotation of the indicating lamps, and to also control the connecting and disconnecting of the indicating lamps from the motor, while additionally controlling the energization of all of the lamps, it is to be noted that variations in speed of the motor will not affect the relative timing in the traffic light. Additionally, since one of the indicating lamps is operatively disconnected from the drive shaft **116**, when the relatively transverse indicating lamp is guidingly connected thereto, it will be appreciated that the gearing utilized to drive the respective indicating lamps may be so constructed that the relatively trans-

versely disposed indicating lamps may be driven at different rates of speeds.

As it is thought that the operation and construction of the device may be readily understood from the foregoing, further description is believed to be unnecessary. However, since numerous modifications will readily occur to those skilled in the art after a consideration of the foregoing specification and accompanying drawings, it is not intended to limit the invention to that shown and described, but all suitable modifications may be resorted to falling within the scope of the appended claims.

Having described the invention, what is claimed as new is:

1. A traffic signal director comprising a housing having first and second relatively transverse traffic control units carried thereby, a motor disposed in said housing and having a vertically disposed drive shaft, each of said units including a "Go" light, a pair of horizontally disposed indicator support shafts carried by said housing, each of said support shafts having an indicator carried thereby and movable around one of said "Go" lights to indicate the time remaining during which the "Go" light will be illuminated, clutch means for drivingly connecting each of said support shafts to said drive shaft, a clutch actuator plate disposed in said housing, a plurality of standards in said housing, means carried by said standards and engaging the periphery of said actuator plate to rotatably support the latter for movement about an axis parallel to the axis of said drive shaft, clutch shifting members movably mounted between said standards and each operatively connected to a different one of said clutch means, said plate having slots therein receiving each of said shifting members, said slots being so constructed and arranged to cause movement of one of said shifting members into its clutch engaging position and movement of the other of said members into clutch disengaging position in response to movement of said plate about its axis of rotation.
2. A traffic signal director comprising a housing having first and second relatively transverse traffic control units carried thereby, a motor disposed in said housing and having a vertically disposed drive shaft, each of said units including a "Go" light, a pair of horizontally disposed indicator support shafts carried by said housing, each of said support shafts having an indicator carried thereby and movable around one of said "Go" lights to indicate the time remaining during which the "Go" light will be illuminated, clutch means for drivingly connecting each of said support shafts to said drive shaft, a clutch actuator plate disposed in said housing, a plurality of standards in said housing, means carried by said standards and engaging the periphery of said actuator plate to rotatably support the latter for movement about an axis parallel to the axis of said drive shaft, clutch shifting members movably mounted between said standards and each operatively connected to a different one of said clutch means, said plate having slots therein receiving each of said shifting members, said slots being so constructed and arranged to cause movement of one of said shifting members into its clutch engaging position and movement of the other of said members into clutch disengaging position in response to movement of said plate about its axis of rotation.
3. A traffic signal director comprising a housing having first and second relatively transverse traffic control units carried thereby, a motor disposed in said housing and having a vertically disposed drive shaft, each of said units including a "Go" light, a pair of horizontally disposed indicator support shafts carried by said housing, each of said support shafts having an indicator carried thereby and movable around one of said "Go" lights to indicate the time remaining during which the "Go" light will be illuminated, clutch means for drivingly connecting each of said support shafts to said drive shaft, a clutch actuator plate disposed in said housing, a plurality of standards in said housing, means carried by said standards and engaging the periphery of said actuator plate to rotatably support the latter for movement about an axis parallel to the axis of said drive shaft, clutch shifting members movably mounted between said standards and each operatively connected to a different one of said clutch means, said plate having slots therein receiving each of said shifting members, said slots being so constructed and arranged to cause movement of one of said shifting members into its clutch engaging position and movement of the other of said members into clutch disengaging position in response to movement of said plate about its axis of rotation, a solenoid operatively connected to said plate for swinging said plate in one direction, means yield-

ingly urging said plate in the opposite direction, and means for selectively actuating said solenoid.

3. A traffic signal director comprising a housing having first and second relatively transverse traffic control units carried thereby, a motor disposed in said housing and having a vertically disposed drive shaft, each of said units including a "Go" light, a pair of horizontally disposed indicator support shafts carried by said housing, each of said support shafts having an indicator carried thereby and movable around one of said "Go" lights to indicate the time remaining during which the "Go" light will be illuminated, clutch means for drivingly connecting each of said support shafts to said drive shaft, a clutch actuator plate disposed in said housing, a plurality of standards in said housing means carried by said standards and engaging the periphery of said actuator plate to rotatably support the latter for movement about an axis parallel to the axis of said drive shaft, clutch shifting members movably mounted between said standards and each operatively connected to a different one of said clutch means, said plate having slots therein receiving each of said shift-
